WILLIAM B. LUCAS, OF OAK PARK, ILLINOIS, ASSIGNOR OF ONE-FOURTH TO GILBERT S. ELLITHORPE AND ONE-FOURTH TO FREDERICK T. ELLITHORPE, BOTH OF CHICAGO, ILLINOIS.

ELECTRIC VAPORIZER AND HEATER.

1,258,231.

Specification of Letters Patent.

Patented Mar. 5, 1918.

Application filed November 30, 1917. Serial No. 204,672.

To all whom it may concern:

Be it known that I, WILLIAM B. LUCAS, a citizen of the United States of America, and a resident of Oak Park, county of Cook, 5 and State of Illinois, have invented certain new and useful Improvements in Electric Vaporizers and Heaters, of which the following is a specification.

This invention relates mainly to heating 10 appliances and to vaporizing means therefor, and more particularly to the generation of steam by electricity.

The main objects of the invention are to provide an improved form of quickly responsive heater and a vaporizer therefor of interchangeable character adapted for quick production of steam and capable of electric operation; to provide a flash generator of improved and compact form adapted for various uses where such a device may be found 20 more readily available and convenient than ordinary sources of steam and especially where quick response is desirable; to provide such a device the mass of which as a 25 whole has a low specific heat, and whereby the initial energy delivered to the generator may be made effective almost instantly throughout the radiator for heating the room; to provide a quick acting electric vaporizer adapted for embodiment in a form suitable for humidifying the air, as in living 30 rooms or wherever the air may be too dry; to provide in a device of the character described, a water supply member adapted for 35 automatic control and electric means for quickly vaporizing the water as it feeds into the device; to provide vapor conduit and discharge means adapted for superheating and delivering the vapor and steam to any 40 particular point desired; and to provide vaporizers and heaters of the character described adapted for ready portability.

Further objects of the invention are to provide steam generating means adapted for 45 attachment to a radiator which may be either connected to independent sources of steam or independent thereof, and which may be either stationary or portable; and to provide a quick-acting steam heater adapted 50 for use in emergency or at times when the regular steam supply or other source of heat is cut off, or where slight or temporary heat may be required at times. Such temporary heat is especially desirable in the

warmer climates as in some of our southern 55 States where permanent heaters are not installed, open fire places often being relied upon.

Usually in the spring and fall there are 60 times when such a device as above referred to may save the labor and expense of starting and operating a furnace or other large equipment temporarily or at a very low efficiency.

Moreover, it not infrequently occurs that 65 one may want immediate, though perhaps only temporarily, sufficient heat to remove the chill, as in a bath room or dressing room. By means of the quick-acting electrically controlled device hereinafter described the 70 foregoing objects may be attained most conveniently and efficiently.

Certain illustrative embodiments of this invention are shown in the accompanying drawings, in which—

Figure 1 is a longitudinal vertical middle section of a room heater or radiator equipped with an electric flash generator having means for superheating the steam.

Fig. 2 is mainly an axial section of an 80 electric vaporizer or steam generator, part of the device being in elevation, same being adapted for use where there is pressure on the liquid supply main.

Fig. 3 is a view similar to Fig. 2 with all 85 of the parts in section.

Fig. 4 is a horizontal section on the line 4—4 of Fig. 3.

Fig. 5 is a vertical axial section of a vaporizer adapted for automatic feed independent of pressure, the general form of embodiment shown being adapted especially 90 for humidifying the air.

Fig. 6 is an axial section of a spirally 95 channeled steam generator adapted for interchangeability with the form shown in Fig. 1.

In the embodiment shown in Fig. 1 the vaporizer or steam generator 1 is attached to a radiator 2 being mounted interiorly 100 thereof. Said radiator is provided with a safety valve 3, an air release valve 4, a current control thermostat 5, and a water feed cup 6. The safety valve is adapted for adjustment to release steam at a predetermined 105 pressure, as will be understood. The air release valve can be of any of the numerous forms adapted to release the air as is usual

in radiators. The thermostat 5 and electrical connections 7-7'-7" leading thereto and to the vaporizer are shown diagrammatically in conventional form, it being understood that the thermostat serves to open the circuit when the temperature rises to a predetermined degree. The feed cup 6 having a removable screw cap 6' is provided in order that the supply of water may be replenished from time to time to take the place of leakage through the air valve, safety device, or otherwise. The radiator may, of course, be provided with a water gage 8 for visual indication of the water level, said gage being on the back side as viewed in Fig. 1.

The radiator 2 may be of any form desired but in the preferred embodiment, such as shown in Fig. 1, it comprises a plurality 20 of sections formed from thin pressed steel plates welded together at their edges as at 9 and 9'. The lower part of the radiator constitutes a reservoir for water as at 10. The upper part comprises numerous sections or steam compartments 11 with open air spaces 12 between them as usual in radiators, thus providing a large radiating surface.

The normal water level is as shown in Fig. 30 1, but this may be permitted to recede to a level indicated at 13, preferably not much if any below the upper edge of the water inlet aperture of the generator 1.

One end of the lower part of the reservoir, 35 preferably opposite from the cup 6, is provided with an interiorly threaded nipple or bushing 14 adapted to receive the vaporizer 1, and the other end may be in a similar manner provided with a nipple 15 adapted to 40 receive the closure or plug 15' which in turn carries the feed cup 6 having a lateral projection threaded to fit in a central perforation in said plug.

The vaporizer of Fig. 1 comprises a closed 45 outer tube or jacket 16 having an aperture 17 on its upper side for the discharge of steam, the outer end of the jacket being interiorly threaded to receive the correspondingly threaded bushing 18. Said bushing is 50 provided with a flange 19 which is clamped by means of the ring 20 against the outer end of the cylindrical plug 21, which fits in the radiator nipple 14. Within the bushing 18 is mounted an insulator 22 in which 55 the current supply wires are embedded, connection thereto from the outer leads 7' and 7" being made through the plug 23, as understood in the art.

As thus applied in the radiator, the vaporizer is mainly concealed so that it does not in any way detract from the attractive appearance of a neat, well-proportioned radiator. Moreover as the heat generating part of the vaporizer is wholly contained within the radiator, the operating condi-

tions are conducive to maximum vapor generating efficiency as there is practically no opportunity for radiation or other dissipation of the heat generated otherwise than directly to the water supplied to the vaporizer. Only a negligible part, if any, of the heat is transmitted along the length of the vaporizer to its base and there radiated to the air.

Referring further to the structure of the 75 vaporizer 1, shown in Fig. 1, the insulator 22, which is made of heat resistant material, preferably clay, porcelain, or the like, is formed with an inwardly projecting hollow tubular part 22' whereon the heat generating 80 resistance conductors 24 are disposed, the wires preferably being substantially embedded in the body of the part 22' or laid on its surface and protected by a suitable glaze, so as to be free from injury by moisture, as 85 understood in the art.

The inner end of the casing 16 is partly closed by an inwardly turned flange 25 thereon, said flange being formed centrally with an opening adapted to serve as an inlet passage for water and being provided with an exteriorly threaded nipple 26 adapted to receive the centrally perforated cap 27. Inside the heat generating tube 22' there is mounted a cylindrical tube 28 in spaced relation thereto, one end of which is closed as at 29, the opposite end being open and fitting tightly within the nipple 26. A packing ring or gasket 30 fits between the cap 27 and the adjacent ends of the nipple 26 and 100 tube 28. Another such ring 30' fits between the end of heater 22' and flange 25. Said tube 28 is provided with outlet apertures 31, preferably in the form of longitudinal slots adjacent to the open end or water inlet. 105 The space 32 between the heater tube and the water inlet tube is occupied by the moisture conducting means 33 opposite the apertures 31 and preferably surrounding the inner tube 28 adjacent to the water inlet end, the 110 other part of the space 32 being open and adapted to serve as a steam chamber and passageway. The said material 33 is preferably porous or wick-like in character, and adapted to cause a gradual feeding of water 115 outward through the apertures 31. Vapor outlet passages or steam ports 34 are provided in the heat generating tube adjacent to the closed end 29 of the tube 28.

The operation of the device shown in Fig. 120 1 is as follows: Water is supplied to the radiator sufficient to nearly cover the vaporizer 1. The electric current is then turned on and almost instantly begins to vaporize the moisture contained in the wick member 33. 125 The steam generated in the wick is thence discharged into the open part of the space between the water tube and the heater element, where it is somewhat superheated as it passes along the inner face of the heater 130

member to the vent ports 34, where it is discharged into the outer chamber 35, between the heater element and the jacket 16, where it is still further superheated and finally discharged through the port 17 into the radiator 2, as indicated by the arrows.

In the embodiment shown in Fig. 2 the vaporizer comprises a water supply tube 41 laterally perforate as at 41" near its upper end, a layer of fibrous material 42 disposed thereon, and an electric heater unit 43 of tubular shape surrounding the fibrous layer. The inner tube 41 is connected to a water supply main 41' and is provided with a shut-off valve 44. The opposite or upper end of the tube 41 is closed by a cap 45 screwed thereon. Packing 46 is provided between the same cap and the heater element to prevent the escape of steam from the upper end 20 of the device. A washer 47 is disposed between the packing and said cap to facilitate clamping the packing tightly in place. The lower end of the heater element 43 bears downwardly against a bushing 48 fitting 25 tightly against the supply pipe and having threaded engagement therewith. The upper end of said bushing 48 is provided with apertures or vents 49 for the escape of the steam descending inside of the heater element. An outer tube or jacket 50 is mounted on said device concentric therewith being supported by a cup-shaped member 51 centrally apertured and secured by a flange or shoulder 48' and a nut 52 on said bushing. 30 35 A steam-tight fit is secured between said bushing and cup member by means of packing washers 53. The upper end of the outer tube 50 may terminate adjacent to the top of the vaporizer in case an instrument is to 40 be used as a humidifier. If the steam is to be used for some other purpose, the said outer tube may be extended to conduct the steam to such point as may be desired, as for instance to a radiator.

45 The water retarding and distributing means or wick member 42 extends over only the upper part of the tube 41, and particularly the perforated part. Heating resistance wire 54 is wound upon the tube 43 and 50 is protected by glaze. The heater is energized by current supplied through the leads 55 and 56, leading to a source 57 and containing a switch 58.

In operation the device is started by turning on the water by valve 44 and also the current by the switch 57. Steam is generated on the wick and passes down into the superheating chamber 59 thence out through the vents 49 and up into the jacket chamber 60 where it is further heated, and finally is discharged upward wherever it may be desired.

In the embodiment shown in Fig. 6, the radiator heater attachment comprises a hollow insulating core 65 on which the resist-

ance wire 66 is carried, preferably being arranged in spiral grooves 67 on the outer surface, an outer shell or casing 68 formed with an interior spiral passageway 69 for the water and steam, a thin waterproof shell 70 surrounding the heater element and fitting within the spirally grooved casing 68, and a layer of heat resistant insulation 71, preferably mica, disposed between the said wires and shell 70.

The outer casing 68 is provided with means for securing the attachment to the radiator, and for this purpose, its base end is exteriorly threaded as at 72 for engaging the interior threads of a bushing 73 which fits in the threaded aperture of the radiator 2 substantially in the manner shown in Fig. 1. Said casing is provided with an inlet aperture 74 for water at one end, and at its opposite end adjacent to the base, is provided with an outlet passage 75 for the steam. The inlet is tubular in shape and provided with a check valve 76. Said valve may be spherical, in which case the inlet aperture is provided with longitudinal slots 77 extending nearly to the outer end, to provide a by-pass for the water, a hollow check nut 78 being provided at the inner end of the aperture to retain the valve in its operative position, and the outer end of the aperture being provided with a hollow nut or bushing 79 provided with a conoidal seat adapted to serve as a port with which the valve coacts. The spiral passageway 69 for the water and steam may be large enough for the water to flow merely by gravity, or it may be relatively small and adapted for capillary action. Although a spiral form for the passageway is preferred, the invention is not limited thereto. When the heater attachment is in place in the radiator, the water level is somewhat above the inlet valve and preferably adjacent to the top edge of the outer casing, but below the orifice of the steam vent. Current supply leads 81 and 82 extend inward through the insulation core 65, one going to each end of the winding, said core being closed at its outer end either by a wall member which may be either integral or in the form of a separate closure disk 83 with the said leads held by said wall in duly spaced relation. The outer ends of said leads may be threaded or otherwise suitably formed and adapted for connection to current supply leads, as understood in the art.

The shell 70 is preferably very thin and may be made of copper or some other good heat conductor, not inclined to rust. The mica insulation is also thin, so that the heat generated is transmitted directly and almost instantly to the passage 69 for vaporizing the water.

In operation the water enters by gravity past the valve 76, and traverses the passage-

way 69. As the water advances it gradually gets hot and finally evaporates before it gets through the passages 69 and in the remaining part of the passage the steam becomes 5 superheated, and is so discharged at 75.

In the form shown in Fig. 5 the device is of simple portable construction, somewhat resembling a wick-lamp. The frame or body 91 of the device comprises a reservoir 92 for 10 water in the lower part, and a vaporizing tube 93 mounted thereon with a wick 94 extending downward from said tube into the water 92'. Mounted on said tube 93 is an electric heater unit or wire 95 adapted for 15 generating sufficient heat to vaporize the water carried up by said wick into the tube 93. The upper end of the tube may be open for the discharge of the steam. This form of the device is especially adapted for use as 20 a humidifier in sick rooms, or other places where artificial moistening of the air may be desired temporarily, and where other sources of steam are not readily available. The electric heater unit may be of any suitable form but preferably comprises a coil 25 of resistance wire embedded and sealed in a porcelain tube substantially as found on the market, said tube being provided with suitable terminals 96 which may be connected as by a cord 97 to any source of electric current of a potential corresponding with the design and current capacity of the heater unit, as for instance to an ordinary lighting circuit, the usual pressure being 30 about 110 volts.

The form of generator and superheater shown in Fig. 2 is especially adapted for humidifying the air, superheated steam being best adapted for that purpose as it does 40 not condense before it can be diffused sufficiently with the air.

Although several specific embodiments of this invention have been herein shown and described, it will be understood that numerous details of the construction shown may 45 be altered or omitted without departing from the spirit of this invention as defined by the following claims.

I claim:

50 1. A flash steam generator and superheater, comprising a plurality of members disposed concentrically in mutually fixed relation, including a centrally disposed water supply tube, a heater unit and a steam conduit in the order enumerated, said supply tube being closed at one end and provided in one part with numerous small discharge apertures, a wick member surrounding the apertured part of said supply tube and filling the space between that part of the supply tube and the heater, the other part or parts of the heater being spaced from the supply tube and steam conduit, whereby the vapor generated in the wick member may 55 pass through the open space in the heater

where it is to some extent superheated, and thence through the chamber between the heater and the steam conduit wall whereby it is still further superheated.

2. A combined steam generator and superheater of the character described, comprising a heater element of tubular form in combination with means for supplying water to the surface of said heater element adjacent to one end, and means for conducting the 75 steam generated past the dry, hot walls of the opposite end.

3. An electric steam generator, comprising a water supply tube closed at one end and provided with lateral apertures for the 80 discharge of water, in combination with a layer of heat resistance porous material surrounding the apertured part of said tube, and a tubular electric heater disposed against and surrounding said material. 85

4. A quick acting device of the character described, comprising a closed radiating receptacle the lower part of which is designed and adapted for holding water, and a gravity feed flash steam combination generator and superheater of unitary character disposed in said receptacle partly above and partly below the normal water level, said generator and superheater comprising an electric heater unit and a guide member having a passageway formed and adapted to conduct water by gravity in a small stream to and against part of said heater unit for quick conversion into steam and also to conduct the steam so formed past another part 100 of said heater unit for superheating same, whereby hot, dry steam may be quickly supplied to said radiating receptacle.

5. A radiator, comprising a closed radiating receptacle having a water reservoir in 105 its lower part into which the receptacle as a whole may drain automatically, and a steam generator mounted in said reservoir and receptacle, said generator comprising an electric heater unit disposed partly below and partly above the normal water level of said reservoir whereby normally it is partly immersed, and guide means disposed adjacent to but spaced somewhat away from said heater unit both below and above the water 110 level, whereby the water is admitted and guided in a small stream to the lower part of said unit and is thence guided upward adjacent thereto and so converted quickly into steam, and is thence discharged into said radiating receptacle above the water level in 115 superheated condition.

6. A radiator adapted to hold water in its lower part, a flash steam generator in said radiator adapted for superheating the steam 120 generated, and means for feeding the water by gravity to said generator.

7. A thin-walled radiator, comprising sheets of pressed metal welded together at their edges and including a relatively small

water reservoir in its lower part, in combination with an electric flash steam generator secured thereto in gravity operative working relation to said reservoir for quick supply 5 of steam in said radiator.

8. A flash steam generator, comprising a pair of tubes disposed one within the other in spaced relation, the one being a liquid supply tube, means pervious to liquid disposed 10 in the space between said tubes, the outer tube being provided with electric heating means and the said one tube having walls pervious to liquid.

9. A flash steam generator, comprising an 15 electric heater, means for feeding water gradually to a part of said heater for vaporization, and means for conducting the resultant vapor and steam past another part of the heater for superheating before dis- 20 charge from said generator.

10. An electric steam generator, comprising a moisture-proof heating element, conduit means formed and arranged to supply water by gravity to said element, and re- 25 stricted guide means adapted to control the discharge of water thereto automatically

substantially in accordance with the rate of evaporation.

11. A quick-acting electric steam radiator having a small mass relative to its effective area and comprising a thin walled sheet metal steam-tight inclosure of unitary character formed and arranged to hold a small quantity of water in its lower part, an electric heater element disposed partly im- 30 mersed and partly above the water level, and a guide shield adjacent to said element formed and arranged to restrict access of the water to the element to a small stream, whereby part of the water may be converted 35 into steam quickly and before the main body of water is heated.

12. A radiator having a chamber provided with water in its lower part, and an electric-heater element disposed with part of its sur- 40 face in contact with the water for generating steam and with the rest of its surface dis- 45 posed out of contact with the water for superheating the steam.

Signed at Chicago this 26th day of Nov. 50
1917.

WILLIAM B. LUCAS.
